UNITED STATES PATENT OFFICE.

EDWARD A. JOHNSTON, OF CHICAGO, ILLINOIS, ASSIGNOR TO MCCORMICK HARVESTING MACHINE COMPANY, OF CHICAGO, ILLINOIS.

HARVESTER-REEL.

SPECIFICATION forming part of Letters Patent No. 737,848, dated September 1, 1903.

Application filed May 13, 1902. Serial No. 107,169. (No model.)

To all whom it may concern:

Be it known that I, EDWARD A. JOHNSTON, a citizen of the United States, residing in Chicago, county of Cook, State of Illinois, have 5 invented certain new and useful Improvements in Harvester-Reels; and I do hereby declare the following to be a full, clear, and exact description of the invention, such as will enable others skilled in the art to which 10 it appertains to make and use the same.

This invention relates to harvester-reels, and especially to the manner of supporting and driving the reels in mowing-machines that are convertible into harvesters or reapers by the attachment thereto of grain-receiving platforms in rear of the cutter-bar. In this class of machines the reel is usually supported at its inner end only and overhangs the cutting apparatus from an up- 15 standing post which rises from the inner shoe. As this shoe rises and falls, and especially when the level of the two shoes changes, the angle of the vertical post varies, so that the lateral position of the gear on the inner end 20 of the reel-shaft changes with respect to the point from which its driving power is taken. As the latter is necessarily a relatively fixed point, some sort of compensating or equalizing gear is necessary to communicate the 25 power to the reel-shaft, and it is to this particular part of the machine that the present invention is confined.

In the accompanying drawings, forming part of this specification, the invention is 30 illustrated in connection with a machine having a slatted platform attached in rear of the cutter-bar and arranged to tilt rearwardly, so as to drop the grain in gavels directly behind the bar, and the invention will be best 35 understood from the following description when taken in connection with these drawings, wherein—

Figure 1 is a plan view of the entire machine. Fig. 2 is a sectional elevation on the 40 line 2 2, Fig. 1, looking in the direction of the arrow. Figs. 3 and 4 are front views illustrating different inclinations from the vertical which the reel-post assumes as the level of the inner and outer shoes changes. 45 Fig. 5 is a detail side elevation of the reel driving and adjusting mechanism only. Fig.

6 is a sectional detail of the gearing at the upper end of the telescopic shaft shown in Fig. 5, and Fig. 7 is a detail front elevation of the same parts.

Referring to the drawings, *a* denotes the inner shoe of a mowing-machine of any preferred type and construction. As usual, it is rigidly attached to the inner end of the finger-bar *b* of the machine, and it is connected by the ordinary hinge-joint *c* with a yoke *d*, which is sleeved on the outer end of the arm *e*, forming one member of a coupling-frame, the construction of which is now quite common in the art and by means of which 55 the cutter-bar and shoe are hinge-jointed to the main frame of the machine.

Rigidly secured to the shoe *a* there is a bracket *f*, which rises vertically from a point near the rear end of the shoe, as best shown 60 in Fig. 2, and the vertical reel-post *g* is secured to the bracket by one or more bolts *h*, so that the weight of the post and the parts carried thereby is entirely supported by the shoe at a point grainward of its hinge-joint 65 connection *c* with the yoke *d*. An additional support for the post and bracket is provided by the strap *i*, which is secured at its forward end near the toe of the shoe and extends upward to the point where the post is secured 70 to the bracket, where the bolt *h* passes through the bracket, the post, and the strap.

The reel-shaft *a'* and its arms or beaters *b'* are journaled in a sleeve *c'*, carried at the outer end of an arm *d'*, which is journaled in 75 a bearing *e'*, that is secured to the post *g* near its upper end. The arm *d'* swings in this bearing and is adjustable at different elevations, so as to raise and lower the position of the reel-arms, a toothed sector-plate *f'* being 80 secured to the post adjacent to the bearing *e'*, into the teeth of which plate a locking-dog on the hand-lever *g'* engages, so as to lock the reel in its different positions.

The power to drive the reel is taken directly 85 from the axle *a'* of the machine, its inner end being provided with a bevel-gear *b'*, having curved teeth *c'*, as best shown in Fig. 6. Sleeved on a trunnion on the outside of the gear *b'*, which is virtually an extension of the 90 axle *a'*, there is a yoke *c'*, having its arm projecting radially in almost opposite direc-

tions, and a similar yoke d^2 is pivoted to the arms of the sleeved yoke and has a bearing e^2 at right angles to the line of the pivot. The yoke d^2 forms the support for the lower end 5 of a telescopic shaft f^2 , which extends diagonally upward and forward to the reel-shaft a' . This shaft consists of a solid portion g^2 , which is angular in cross-section and slides within a tubular portion, and in the preferred 10 construction the tubular portion is journaled at its lower end in the bearing e^2 of the pivoted yoke d^2 . Secured to the upper end of the tubular portion f^2 is the collar f^{21} , which is provided with an opening of a cross-section 15 corresponding to that of the solid portion g^2 , which fits therein. This diagonal shaft transmits driving power to the reel-shaft from the gear b^2 on the axle of the machine, the connection between the gear and the shaft being 20 made by a bevel-gear h^2 , secured on the lower end of the shaft below the bearing e^2 and between the arms of the yoke d^2 . The teeth of the gear h^2 are curved reversely with respect to the curvature of the teeth of the gear b^2 , 25 and the point of tangency of pitch-lines of the intermeshing teeth of these two gears is arranged, as best shown in Fig. 6, in line with the pivots between the arms of the two yokes c^2 and d^2 , the object of this arrangement being 30 to permit the diagonal shaft to change its angle with respect to the axle of the machine without causing the gears to bind or interfere with their free driving action.

At the upper end of the telescopic shaft f^2 35 there is a bevel-gear a^3 , having crown-shaped teeth, which are in all respects like the teeth of the gear h^2 at the lower end of the shaft. This gear intermeshes with a similar pinion b^3 on the reel-shaft a' , and the upper end of 40 the telescopic shaft is united to the reel-shaft by means of yokes c^3 and d^3 . The yoke c^3 is journaled upon the projecting end of the reel-shaft a' outside of the gear b^3 and has radial arms e^3 f^3 extending substantially in opposite 45 directions, by means of which it is pivotally connected to similar arms g^3 h^3 on the yoke d^3 .

The arrangement for supporting and driving the gears, by means of which the upper 50 end of the telescopic shaft is connected to the reel-shaft, is the same, in all essentials like that at the bottom of the shaft, where it is connected to the axle of the machine by the intermeshing gears b^2 and h^2 .

55 The yokes c^{21} and c^3 rock on their respective shafts as the position of the reel is raised or lowered, thereby permitting the diagonal telescopic shaft to accommodate its angular position to the different elevations of the reel, 60 and the pivotal connection between the arms of the yokes c^{21} c^3 permits the diagonal shaft to change its position relative to a vertical plane, as the lateral position of the reel-shaft gear is altered by the rising and falling of the 65 cutting apparatus as a whole or of the change in level between the inner and outer ends of the cutter-bar.

Fig. 4 illustrates a machine working on level ground with both ends of the bar at the same elevation. In this position the reel-post is truly vertical, and the reel drive-shaft f^2 occupies nearly a vertical plane fore and aft of the machine. Any elevation of the cutting apparatus, and especially any such elevation of the outer end of the finger-bar, 70 as indicated in Fig. 3, tilts the reel-supporting post g over toward the stubble side of the machine, and in order for the telescopic shaft to drive the reel-shaft in its tilted position it is necessary that it should move bodily with 75 the reel-post. This lateral movement of the diagonal shaft is permitted by means of the yokes d^2 and d^3 being pivotally connected by their arms, respectively, to the arms of the yokes c^2 and c^3 on lines at right angles to the 80 pivotal connection of the latter yokes with the axle of the machine and the reel-shaft. The diagonal shaft has therefore a universal-joint connection at its lower end with the part which drives it and at its upper end with 85 the part which is driven by it, and the result of this connection is that the length and position of the shaft will automatically accommodate itself to the vertical adjustments of the reel, and the shaft will also accommodate 90 itself as regards its lateral position and inclination with the tilting movements of the reel-post due to the causes already mentioned.

Having thus described my invention, what I claim, and desire to secure by Letters Patent, is—

1. The combination with the inner shoe of a mower, of a post rising therefrom, a reel supported by said post, a gear on the inner end of the axle of the machine, a gear on the reel-shaft, and a line-shaft having gears at opposite ends meshing with the gears on the machine-axle and reel-shaft, and yokes in which the line-shaft is journaled at its ends said yokes pivoted on a line passing through 105 the points of tangency of the pitch-lines between the gears.

2. The combination with the inner shoe of a mower, of a post rising therefrom, a reel supported by said post, a yoke on the inner 115 end of the axle of the machine, a similar yoke on the reel-shaft, gears on the axle and reel-shaft adjacent to said yokes, and a line-shaft having gears at its ends meshing with the gears on the axle and reel-shaft, said line-shaft being journaled at its ends in yokes pivoted to the first-named yokes in a line 120 passing through the points of tangency of the pitch-lines between the gears.

3. The combination with a reel-post, of a 125 reel and its shaft adjustably supported on the post, a telescopic driving-shaft pivoted at its lower end, intermeshing gears on the reel-shaft and upper end of the telescopic shaft, a yoke journaled on the reel-shaft and having oppositely-projecting radial arms, and a 130 similar yoke in which the upper end of the telescopic shaft is journaled, said yokes being pivotally connected by their arms on a

line passing through the points of tangency of the pitch-lines between the gears.

4. The combination with a reel-post, of a reel and its shaft adjustably supported on the post, a telescopic drive-shaft having a gear connection with the reel-shaft, a yoke journaled on the inner end of the axle of the machine and having oppositely-projecting radial arms, a similar yoke in which the lower end of the telescopic shaft is journaled, and intermeshing gears connecting the axle and telescopic shaft, said yokes being pivoted together by their arms on a line passing through the points of tangency of the pitch-lines between the gears.

5. The combination with the inner shoe of

a mower, of a post rising therefrom, the reel supported by said post, a gear on the reel-shaft, a gear on the inner end of the axle of the machine, a line-shaft having gears at its opposite ends meshing respectively with the gears of the reel-shaft and the machine-axle, and universal-joint connections between the reel-shaft and axle, respectively, and the line-shaft, said connections including yokes enclosing the line-shaft gears.

In testimony whereof I affix my signature in presence of two witnesses.

EDWARD A. JOHNSTON.
